DESIGN FOR A MECHANIC'S SQUARE

Claude H. King, Detroit, Mich.

Application August 25, 1943, Serial No. 110,992

Term of patent 3½ years

To all whom it may concern:

Be it known that I, Claude H. King, a citizen of the United States, residing at Detroit, county of Wayne, in the State of Michigan, have invented a new, original, and ornamental Design for a Mechanic's Square, of which the following is a specification, reference being made to the accompanying drawing, forming part thereof.

Fig. 1 is a side elevation of a mechanic's square, embodying my new design.

Fig. 2 is a rear elevation thereof.

Fig. 3 is a front elevation thereof.

Fig. 4 is a bottom plan view thereof.

Fig. 5 is a perspective view thereof.

I claim:

The ornamental design for a mechanic's square, as shown.

CLAUDE H. KING.
